UNITED STATES PATENT OFFICE.

WILLIAM A. KIRKPATRICK AND CHARLES E. POORMAN, OF ABBYVILLE, KANSAS.

DISPENSING-CONTAINER.

1,039,756.

Specification of Letters Patent.

Patented Oct. 1, 1912.

Application filed April 13, 1912. Serial No. 690,542.

To all whom it may concern:

Be it known that we, WILLIAM A. KIRKPATRICK and CHARLES E. POORMAN, residing in the city of Abbyville, county of Reno, 5 and State of Kansas; have invented a new and Improved Dispensing-Container, of which the following is a specification.

This invention relates to that class of containers more especially adapted for holding 10 drinking straws, such as are served at drinking bars and soda fountains, and from which said straws are delivered singly from a closed receptacle.

The primary object of our invention is to 15 provide an appliance of the character stated, of a simple, ornamental, and economical construction, that serves to hold the straws and to discharge them while in their upright position, and for being conveniently with- 20 drawn by the user.

Another object of our invention is to provide a container operating under a plunger action, that automatically ejects a single straw under each plunger action and adjusts 25 the remaining straws therein contained for being positively and singly engaged by the ejecting means under each return movement of the container.

Another and important object of this in- 30 vention is to provide a yieldable covering for the discharge of the container, and so arranged, whereby, while providing for the passage therethrough of the ejected straws, it acts as a guide for the straws while they 35 pass up out of the container and as a closure for the straw discharge to render it dust proof.

With other objects in view that will hereinafter appear, our invention comprises an 40 appliance of the character and for the purposes stated, that embodies the peculiar and novel arrangement of the parts, hereinafter fully explained, specifically pointed out in the appended claims and illustrated in the 45 accompanying drawing, in which:—

Figure 1 is a perspective view of our invention, and it illustrates the manner in which it is manipulated to deliver a straw. Fig. 2 is a vertical section of the same the 50 parts being at their extended or normal

position. Fig. 3 is a similar view the container being shown as partly plunged down to eject a straw. Fig. 4 is a horizontal section of the same on the line 4—4 on Fig. 2. Fig. 5 is a perspective view of the container 55 with the cap or top member removed. Fig. 6 is a detail view of the yieldable closure for the top or cap member. Fig. 7 is a detail sectional perspective view of one of the spring connections for the container or 60 holder.

In carrying out our invention, the holder or supporting portion 1, together with the container, are arranged in an upright position, and the ejecting means is such that the 65 straws are pushed out, one at a time, through the top or cap member of the container and to such an extent that they may be conveniently pulled out by the user, see Fig. 1.

The support or holder and the container 70 may be made of sheet metal, but for sanitary and ornamental reasons we make the body of the container of glass. The supporting member or holder 1 is of sheet metal, of tubular form and is secured at the bottom 75 to a solid metal base 11, of sufficient weight to withstand the impact of the container with the support, on the return or rebound movement of the said container; as will hereinafter more fully appear. The container 80 2, is of a diameter to freely fit and move in the holder 1 and to avoid undue rubbing of the glass and metal members, the upper end of the holder 1 has a yieldable covering 12 of felt or other suitable material. 85

20 designates the bottom of the container, preferably a wooden member that is secured in the lower end of the glass container in any approved manner. The bottom 20 has a cone-shaped or dished upper face and a 90 central aperture 21, for riding over a permanently secured ejector 3, in the nature of a stout rod that is made fast to the bottom plate and has its upper end cone-shaped, as at 30, and normally projected flush with the 95 centrally depressed portion of the container bottom, whereby, to be in position for riding into the open end of the selected one of the straws when the container 2 is moved or plunged down into the holder 1. 100

When made of glass, the upper end of the container is externally threaded to receive the threaded pendent flange 22, of the glass cap or top 23, that is also cone-shaped but inversely positioned with respect to the dished bottom 20. The top 23 has a central discharge outlet 24, of much greater diameter than that of a single straw, whereby to avoid the danger of breaking or bending the straws as they rise on the incline top toward the said discharge opening.

For rendering the container 2 dust proof and also to act as a guide for holding the straws at a substantially perfect vertical position, as they move out of the container, a felt disk 4 is glued or otherwise secured upon the top 23, and over the outlet 24, and the said disk at its apex is crosswise slotted, as at 40, to allow the straw pushing up through the said disk. By reason of slitting the disk 4 as stated, the cut edges or flaps of the disk come together and form a closure for the opening in the top 23 and thereby excludes dust and dirt from entering the container through the said top opening, and further the said flaps act as a guide for the straw when the latter pushes out between them since they grip the straw under sufficient pressure to hold it to the center.

30. The container 2 is normally moved upwardly and held to its extended position under spring tension and for such purpose we employ two coiled springs 5 that are oppositely disposed and held within the vertically extended pockets 14, formed in the holder 1, the lower ends of which terminate at the long slots 15 and the upper ends at the hooks 16 that are formed by slitting the upper end of the holder 1 and bending the cut portions inwardly. The upper ends of the springs are secured to the hooks 16 and the lower ends to the headed screw studs 17, that ride in the slots 15, pass through apertures in the lower end of the container 2 and screw into the bottom 20 as shown.

From the foregoing taken in connection with the drawing, the complete construction, the manner of its use and the advantages of our invention will be readily apparent. The 50 user simply has to plunge the container down into the holder, see Fig. 1, a distance sufficient to cause the straw to push up through the top of the container, when it is gripped and held by the yielding disk covering, ready to be pulled out. When the container is released the springs 5 quickly moves it up until the studs 17 engage the upper ends of the slots 15, which not only holds the container in proper position with 55 respect to the ejector rod but creates an impact or shock sufficient to cause the lower ends of the straws within the container to seek the center of the dished bottom and thereby bring one of them directly in line

with the conical end of the ejector, it being 65 obvious that when the container is moved down, the cone end of the ejector fitting into a straw, holds the straw up and pushes it through the yielding covering 4, at the top.

While we have described our invention as 70 especially designed for dispensing drinking straws, with slight modifications it may be well adapted for dispensing other singly dischargeable commodities.

What we claim is:

1. In an apparatus as described, a container having a dished bottom provided with a centrally disposed aperture, a holder for the container, means mounted in the holder and co-operating with the container for normally forcing the said container outwardly from the holder, a fixedly held ejector that extends into the central aperture of the container bottom for engaging a straw to hold it when the container is forced into the holder, 80 said container having a conical cap provided with a central outlet for the passage of the straw held by the ejector, and a flexible covering for the passage slitted to allow the straw to frictionally pass therethrough. 90

2. In an apparatus of the character described, a container having an outlet in the upper end and a dished incline to the said outlet, and a dished bottom, the said bottom having a central opening, a holder for the 95 container, a plunger having a conical end that normally seats in the central opening in the dished bottom of the container and spring connections that join the holder and the container for normally thrusting the 100 container to its outermost position, said holder having laterally projecting chambered portions for receiving said spring connections and forming a housing therefor.

3. In a dispensing appliance of the character stated, a container having means at the bottom for directing the lower ends of the drinking tubes to the center of the bottom, said bottom having a central passage, the container having an outlet at the upper 110 end, and means for directing the straw to be ejected toward the outlet, means over the outlet for frictionally engaging the projected straw, a fixed ejecting finger that projects into the passage in the bottom of the 115 container and engages the inner edge of the lower end of the central straw, a holder for the container into which the latter is plungable, and means connected with the holder and the container for normally thrusting the 120 container to its outermost position.

4. In an appliance of the character stated, a holder, a container plumbable into the holder, means coacting with the container for ejecting articles therefrom when it is 125 forced down into the holder, other means for normally moving the container to its out-thrust position, said means comprising ver-

tically disposed pockets in the holder, said pockets each being longitudinally slotted and having their upper ends formed with inwardly bent hooks, screw studs that pass through the slots and engage the base of the container and coiled springs that ride in the pockets and have one end secured to the

screw studs and the other end to the hooks on the holder.
